LAMP

Filed Feb. 7, 1927

UNITED STATES PATENT OFFICE.

FRANK L. BAMFORD, OF DETROIT, MICHIGAN, ASSIGNOR TO C. M. HALL LAMP COMPANY, OF DETROIT, MICHIGAN, A CORPORATION OF MICHIGAN.

LAMP.

Application filed February 7, 1927. Serial No. 166,541.

The invention relates to lamps and is particularly applicable to head lamps. One of the objects of the invention is to provide a simple and compact device for adjusting the light bulb longitudinally and transversely of its axis. Another object is to provide an adjusting device, the parts of which may be readily assembled or disassembled. With these as well as other objects in view, the invention resides in the novel features of construction and combinations and arrangements of parts as more fully hereinafter set forth.

In the drawings:

15 Figure 1 is a longitudinal section through a lamp, showing in elevation a device embodying my invention, for adjusting the light bulb longitudinally and transversely of its axis;

20 Figures 2 and 3 are longitudinal sections at right angles to each other through the device;

Figure 4 is a perspective view thereof; and

Figure 5 is a transverse sectional view taken substantially on the line 5—5 of Figure 3.

1 1 is the body of the lamp, 2 the reflector, 3 25 the light bulb and 4 the socket for the bulb. This socket is mounted upon the reflector so that it may be adjusted longitudinally and transversely of its axis to correspondingly adjust the bulb, and as shown, the mounting 30 for the socket comprises the tubular member 5 rigidly secured at one end to the reflector and having the diametrically opposite longitudinally extending slots 6 with open rear ends. The socket 4 is provided with projections 35 7 for engaging in these slots and providing for swinging of the socket at right angles to the line passing through the projections, the tubular member being made elliptical to provide the necessary clearance for 40 this swinging movement. These projections are also adapted to slide longitudinally in the slots to provide for adjustment of the socket longitudinally of its axis.

45 The device for adjusting the socket and consequently the light bulb longitudinally and transversely of its axis has the supporting yoke 8 which is provided with the resilient arms 9 having their ends embracing the tubular member 5 and covering the slots 6 therein. These ends are adapted to be detachably connected to the tubular member and as shown the end of each arm is formed with transverse recesses 10 and the tubular member 5 is formed with the transverse 50 struck out tongues 11 for engaging in the re-

cesses. For normally holding the arms connected to the tubular member, I have provided the transverse tie member 12 which extends between the arms and through openings 13 therein and has hooks 14 at its ends 60 for engaging the outer sides of the arms. 15 is a yoke having its base secured to the rear end of the socket 4 and having its arms 16 extending between the planes of the arms 9 of the supporting yoke 8, the two yokes 65 extending at right angles to each other.

For actuating the yoke 15 to adjust the socket longitudinally and transversely of its axis, I have provided the concentric inner and outer actuating members 17 and 18 respectively. The actuating member 18 extends through the base of the supporting yoke 8 and is held from longitudinal movement by means of the clip 19 and the base of the supporting yoke embracing the collar 20 70 upon this actuating member. This actuating member has its front end threaded and engaged by the nut 21. The nut 21 has the ears 22 extending from its opposite sides and through openings 23 at the free ends of the arms 16. These ears are preferably curved to be concentric with the projections 7 so that they will not interfere with the rocking of the socket and light bulb. The inner actuating member 17 extends through the outer actuating member and has rigidly secured to its front end the cam 24 which is located between the arms 16 and is engageable therewith to effect the rocking of the socket and light bulb. 75 25 is a coil spring surrounding the front ends 80 of the actuating members 17 and 18 and abutting the nut 21 and the cam 24 to resiliently hold this cam against the tie member 12 and consequently hold the tie member from accidental disengagement from the arms 9 of the 85 supporting yoke. The arms 16 are preferably made resilient to provide for applying or detaching these arms to or from the ears 22 of the nut 21. However, the strength of the arms is such that they do not flex upon 90 engagement by the cam. The rear ends of the actuating members 17 and 18 are preferably slotted so that they may be readily rotated by means of a screw driver.

The actuating members are in alignment 105 with the opening 26 in the rear of the lamp body 1, this opening also being in alignment with the socket and light bulb. As shown, the rear end of the outer actuating member 18 is substantially flush with the lamp body 1 110

but this is not essential as long as the actuating members are in alignment with the opening in the lamp body.

When it is desired to adjust the socket longitudinally of its axis, a suitable tool is engaged with the notch in the member 18 for rotating the same which will thread the nut 21 thereon and by reason of the connection between the nut and yoke 15, axial adjustment of the socket will be effected. Transverse adjustment of the socket is accomplished by rotation of the actuating member 17 which will cause the cam 24 to operatively engage the arms of the yoke 15 to rock the socket in a plane transverse to the axis thereof.

It will be seen from the above description that I have provided a simple compact construction of device providing for the adjustment of the light bulb longitudinally and transversely of its axis, this transverse adjustment being in a vertical direction. It will also be seen that the parts of this device may be readily assembled or disassembled owing principally to the fact that the arms of the yokes are resilient. It will furthermore be seen that the construction is such that certain of the parts such as the nut, the clip and the tie member may be readily formed of stampings and that the other parts may also be cheaply manufactured.

What I claim as my invention is:

1. In a lamp, the combination with a reflector, a light bulb within said reflector and a socket for said bulb fulcrumed upon said reflector, of a yoke upon said socket having resilient apertured arms, concentric actuating members including a threaded member, a nut upon said threaded member and having ears at its opposite sides engageable in the apertures in said arms for adjusting said socket longitudinally of its axis upon rotation of said threaded member, and a cam upon the other of said members located between said arms and engageable therewith to adjust said socket transversely of its axis upon rotation of the member upon which it is mounted, the strength of said arms being sufficient to normally hold the same from flexing upon engagement by said cam, but permitting the manual disengagement of said arms from said ears.

2. In a lamp, the combination with a reflector, a light bulb within said reflector and a socket for said bulb fulcrumed upon said reflector, of a supporting yoke having arms detachably connected to said reflector, a tie member extending between said arms and detachably engageable therewith for holding the same connected to said reflector, a rotatable actuating member, means for rocking said socket upon rotation of said actuating member including a cam upon said actuating member, and a common means for normally holding said actuating member from longitudinal movement and said tie member from disengagement from said arms.

3. In a lamp, the combination with a reflector, a tubular member upon said reflector, a light bulb within said reflector and a socket for said bulb fulcrumed upon said tubular member, of a supporting yoke having resilient apertured arms for detachably engaging said tubular member, a tie member extending through apertures in said arms and having hooks at its opposite ends for engaging said arms to hold the same in engagement with said tubular member, a rotatable threaded actuating member, means cooperating with said supporting yoke to hold said actuating member from longitudinal movement relative to said supporting yoke, means for adjusting said socket longitudinally of its axis including a nut upon said actuating member and between said arms, a second actuating member concentric with said first mentioned actuating member including a cam for rocking said socket transversely of its axis, and a coil spring extending between said nut and cam and resiliently holding said cam against said tie member to retain said tie member from accidental disengagement from said arms.

4. In a lamp, the combination with a reflector, a light bulb within said reflector and a socket for said bulb fulcrumed upon said reflector, of a supporting yoke detachably mounted upon said reflector, a combined tie and bearing member engaged with the arms of said yoke for holding said yoke upon said reflector, concentric actuating members including a threaded member, one of said actuating members being journaled upon said yoke and the other upon said combined tie and bearing member, a yoke upon said socket, a nut upon said threaded actuating member engageable with the arms of said second-named yoke for adjusting said socket longitudinally of its axis upon rotation of said threaded member, and a cam upon the other of said actuating members located between said arms and engageable therewith to adjust said socket transversely of its axis upon rotation of the actuating member upon which it is mounted.

5. In a lamp, the combination with a reflector, a light bulb within said reflector and a socket for said bulb fulcrumed upon said reflector, of a supporting yoke detachably mounted upon said reflector, a combined tie and bearing member engaged with the arms of said yoke for holding said yoke upon said reflector, an actuating member journaled in said combined tie and bearing member, a yoke upon said socket, and a cam upon said actuating member engageable with the arms of said second-named yoke for adjusting said socket transversely of its axis upon rotation of said actuating member.

6. In a lamp, the combination with a reflector, of a light bulb within said reflector

and a socket in said bulb fulcrumed upon said reflector, of a supporting yoke detachably mounted upon said reflector, a tie member detachably engaged with the arms of said yoke 5 for holding said yoke upon said reflector, a rotatable actuating member extending through said yoke, resilient means for normally holding said actuating member against longitudinal movement and said tie member 10 from disengagement from said arms, and means between said actuating member and socket for rocking said socket upon rotation of said actuating member.

7. In a lamp, the combination with a reflector, a light bulb within said reflector and

a socket for said bulb fulcrumed upon said reflector, of concentric actuating members including a threaded member, a nut upon said threaded member for adjusting said socket longitudinally of its axis upon rotation of 20 said threaded member, a yoke upon said socket having arms connected to and movable on said nut, and a cam upon the other of said actuating members located between said arms and engageable therewith for moving said arms to adjust said socket transversely of its axis upon rotation of the actuating member 25 upon which it is mounted.

In testimony whereof I affix my signature.

FRANK L. BAMFORD.
